UNITED STATES PATENT OFFICE.

CHARLES PEARSON, OF CHICAGO, ILLINOIS, ASSIGNOR TO INTERNATIONAL HARVESTER COMPANY, A CORPORATION OF NEW JERSEY.

FLEXIBLE PITMAN HEAD.

Application filed July 1, 1925. Serial No. 40,712.

This invention pertains generally to pitman connections and more particularly to a pitman connection adapted for use in connection with mowing machines and the like.

Mowing machines, as now known in the art, embodying a reciprocatory cutter bar, have such cutter bars provided with a so-called knife head and this knife head is provided with a bearing member which is coupled by means of a pitman to a crank or wrist pin carried by a crank disk fly wheel fixed to a driving shaft. As is usual in these constructions, during normal operation on an even field, this crank pin is in parallel alinement with the longitudinal axis of the mowing machine and lies substantially in a horizontal plane. The knife or cutter bar in its normal position of adjustment is reciprocated in a direction transversely or perpendicularly of the line of draft. These pitmen are sometimes of a rigid construction and when positioned as just described will usually operate under favorable conditions in a fairly satisfactory manner. Difficulty is, however, encountered in the operation of such pitmen when the cutter bar is adjusted out of its normal position, that is, when the same is tilted out of a horizontal plane by changing the lead of the cutter bar, for then strains of torque must be resisted by such pitmen and, as a consequence, they will not operate successfully, such strains frequently causing breakage of the pitmen. They will also fail to operate efficiently when the tongue of the mower is raised or lowered thereby tilting the crank pin up or down. This objection as just described has been overcome to some extent in the provision of a pivoted or jointed upper end construction; but such jointed upper end is likewise objectionable as the strains of use soon cause wear and breakage.

An object of the present invention is to overcome the difficulty by some means other than by a pivoted or jointed upper end construction and to provide a pitman which will be non-jointed and flexible under strain in certain directions but will be rigid and inflexible under strains in other directions. Another object is to provide a pitman construction of the kind specified, the upper end of which will be non-jointed and of simple construction and which may be readily manufactured for commercial use at a minimum of expense.

Still a further object is to provide an improved bearing box for such a pitman embodying a novel means for preventing unloosening of the parts comprising said bearing box.

Other objects will be apparent to those skilled in this art as the description hereof progresses.

Briefly, the objects of this invention are accomplished in the provision of the usual wooden pitman body, having a flat, flexible, non-jointed metallic extension secured thereto at one end, said extension carrying at its free end at a point spaced from the body of the pitman, a two part bearing boss, said parts being interlocked and having disposed therebetween a means for preventing unloosening thereof.

In the accompanying sheet of drawings, wherein the preferred embodiment of this invention has been illustrated and wherein like characters of reference designate similar parts,

Fig. 1 is a plan view of that end of the pitman which is connected to the crank disk or fly wheel of a mower;

Fig. 2 is a similar view showing the bearing box in section when viewed along the line 2—2 in the direction of the arrows shown in Fig. 3;

Fig. 3 is a side view of the construction shown in Figs. 1 and 2;

Fig. 4 is an end view of the bearing box;

Fig. 5 is a view similar to Fig. 4, but shown in section as viewed along the line 5—5 shown in Fig. 1; and

Fig. 6 is a plan view of the novel locking means utilized in this invention.

As shown in the drawings, the conventional wooden body 10 of a pitman is shown, the upper end of which is slotted for the reception of a flat metallic, and preferably steel, extension 11, said extension being securely fixed to the body 10 by a plurality of rivets 12. The flat extension 11 is tapered as shown, whereby the same is capable of having a graduated resiliency, as will be understood. The free end of the flat member 11 is apertured to receive a novel form of bearing box in which is journaled, as is usual in this art, the crank pin carried by the crank disk mounted on the mower drive shaft.

This bearing box is made up of two pieces, one of the pieces being a sleeve-like member

13 having a threaded bore conforming substantially with the size of the aperture in the extension 11. This member is placed against the flat extension, as shown in Fig. 5, and a cooperating sleeve member 14 having a through opening, and a mated threaded extension 15 is then fitted through the flat extension from the opposite side and screwed into the piece 13, the member 14 furthermore having a polygonally shaped nut or wrench engaging portion 16. As shown, the member 13 has an upstanding bored out boss 17, which is adapted to be provided with any conventional appliance for applying lubricant to the bearing box. The two pieces 13 and 14 are also formed to provide an annular lubricant containing chamber 18 in communication with the bore in the boss 17, said chamber 18 communicating with the interior of the bearing box and the wrist pin journaled therein, by means of apertures 19. The boss 17 is provided on its upper end, and in a direction extending toward the member 14, with a small shoulder 20 for a purpose to be presently described.

Due to the severe use to which a bearing box of this kind is subjected, it is quite unlikely that the threaded engagement between the two pieces making up the bearing box will be sufficient to secure the parts together and there is, therefore, provided a novel form of locking means in the form of a washer for insuring a positive retention of the parts forming the bearing box in proper position. This locking means is in the form of a washer indicated generally at 21, as shown in Fig. 6, the same being centrally apertured and having two wings 22 on its upper side and a plurality of segmental flaps 23 arranged along the remainder of its periphery, as shown. Before securing the piece 14 into the piece 13, this lock washer is placed in position, as shown in Fig. 5, against the flat extension with the flaps 22 bent back to straddle the boss 17 on each side of the shoulder 20. The parts 13 and 14 are then screwed together clamping the washer therebetween, thus providing a means which will prevent rotation of the member 13. The member 14, by means of a wrench, may then be tightened as far as possible, so that one of the flaps 23 will be in a position to be folded backwardly in a direction to engage one of the polygonal faces of the wrench engaging portion 16, thereby

preventing rotation of the member 14 and unloosening thereof. It will thus be appreciated that the lock washer, which is made of easily bendable material and in the form of a stamping, is provided with means which may be oppositely disposed to lock the oppositely disposed pieces of the bearing box and thereby prevent relative rotation of the parts with respect to each other.

Due to the construction of the extension 11, as above described, it will be seen that a construction has been provided by means of which a lateral flexing of the pitman is permitted, but a flexing at right angles to this direction is prevented. The metallic strip 11 is purposely made wider at its end adjacent the bearing box to prevent any flexing in a horizontal plane parallel to the line of draft, whereas any lack of alignment between the crank pin and the knife head, as when the cutter bar is tilted, is compensated for by the flexible connection. As there are no moving parts, that is, as this upper end is non-jointed, there can be no friction and wear to cause breakage.

While in the above specification only the preferred embodiment of this invention has been shown and described, it is to be understood, of course, that the same is capable of modification and changes, and, therefore, changes in the construction and arrangement of parts may be made without departing from the spirit and scope of this invention as expressed hereinafter in the claims.

What is claimed is:

1. In a pitman comprising a body and a flat, flexible, metallic extension secured to one end thereof, the combination of a bearing box made of two parts screw threaded together and clamping the extension between them to mount the box, and means causing oil to be circulated in the interior of the box.
2. In a pitman comprising a body and a flat, flexible, metallic extension secured to one end thereof, the combination of a bearing box comprising two parts screw threaded together and clamping the extension between them to mount the box, means preventing accidental rotational relative loosening movement between the parts, and means causing oil to be freely circulated in the interior of the box.

In testimony whereof I affix my signature.

CHARLES PEARSON.
